ATTORNEY

UNITED STATES PATENT OFFICE.

RICHARD A. FINIS, OF SAN FRANCISCO, CALIFORNIA, ASSIGNOR TO THE HI-SIGN SIGNAL COMPANY, OF STOCKTON, CALIFORNIA, A CORPORATION.

MULTIPLE-CONTACT ELECTRIC SWITCH.

Application filed June 16, 1922. Serial No. 568,795.

To all whom it may concern:

Be it known that I, RICHARD A. FINIS, a citizen of the United States, residing at San Francisco, county of San Francisco, 5 State of California, have invented certain new and useful Improvements in Multiple-Contact Electric Switches; and I do declare the following to be a full, clear, and exact description of the same, reference being had to the accompanying drawings, and to the characters of reference marked thereon, which form a part of this application.

This invention relates to improvements in electric switches of the push-button type 15 adapted to be manually manipulated. The principal object of my invention is to provide a switch so constructed that depression of the button a certain distance will close a circuit, while further depression of the 20 button will break said circuit and close another one.

Another object is to arrange a number 25 of such switches in cooperative relation in such a manner that with a single lead from a source of current to one of the switches, any of the switches may be actuated at will when the buttons of those between the lead and the switch being actuated are in their normal and inactive positions. In other 30 words, the normal positions of the buttons, of said intermediate switches controls the flow of current to the switches beyond, while not necessarily causing any circuit to be closed.

35 My multiple switch system is especially intended and designed for use with a signal system for automobiles, in which signal system I contemplate giving, by means of different lights, a number of signals, such as "stop," "back," "right," and "left" visible 40 both from the front and rear of the car, which signals will be flashed by the driver of the car at the proper time by pressing the button of the particular switch which 45 controls the signal desired.

I have also provided means independent of the switch buttons for enabling the "stop" signal being automatically flashed when the brake of the car is applied, the 50 current to then actuate the signal passing however through the single lead common to all the switches.

These objects I accomplish by means of such structure and relative arrangement of

parts as will fully appear by a perusal of the following specification and claims.

In the drawings similar characters of reference indicate corresponding parts in the several views.

Fig. 1 is a perspective view of the multi- 60 ple-switch box as arranged for use with the signalling system.

Fig. 2 is a sectional elevation of one of the switches.

Fig. 3 is a diagram of the circuits em- 65 ployed with the switches and signalling system.

Fig. 4 is a fragmentary perspective view of a special type of switch-contacts.

Referring now more particularly to the 70 characters of reference on the drawings, the numeral 1 denotes a casing of suitable dimensions and preferably formed of some insulation composition material, and in which the various switches are located, said 75 casing having a clamp member 2 whereby it may be mounted in connection with the steering column of an automobile.

In the present instance, I employ four 80 switch units 3, 4, 5 and 6, which control the "right," "back," "left" and "stop" signals respectively. Switches 3, 4 and 5 are identical in construction, while switch 6 is of somewhat different design though working 85 on the same principle as the remainder.

Switches 3, 4 and 5 comprises push buttons 7, 7^a and 7^b projecting through the upper face of the casing, bearing on, and normally held in their outermost position by, spring strips 8, 8^a and 8^b free at one end 90 and fixed to the top of the casing at the other.

The fixed end of strip 8 of the switch 3 is connected to a lead 9 from a source of current 10, and normally contacts at its free 95 end with the free end of the strip 8^a, while the free end of the latter normally contacts with the fixed end of the strip 8^b.

Under the strips 8, 8^a and 8^b and fixed 100 to the bottom of the casing are other spring strips 11, 11^a and 11^b respectively, insulated from each other. These strips tend to move upwardly and normally contact at their free ends with members 12, 12^a and 12^b, arranged 105 to prevent such upward movement of the strips. Under said strips and normally spaced therefrom are contacts 13, 13^a and 13^b respectively. Fixed to the casing in

common with the strips 11, etc., and contacting therewith at their fixed ends are intermediate spring strips 14, the free ends of which are normally spaced both from the upper strips 8, etc., and from the lower strips 11, etc.

The switch 6 comprises a button 15 pressing against a strip 16 similar to the strips 8, etc., and contacting at its fixed end with the free end of the adjacent strip 8^b, and at its free end with a contact member 17.

Under the strip 16, and fixed to the bottom of the casing are a pair of spring strips 18 and 18^a, insulated from each other, which normally contact with members 19 and 19^a fixed in the casing and likewise insulated from each other. Under the strips 19 and 19^a are contacts 20 and 20^a, normally spaced therefrom and insulated from each other. Above the strips 18 and 18^a are intermediate strips 21, fixed in common with the strips 18 and 18^a and contacting therewith at their fixed ends, but insulated from each other. These strips 21 are normally spaced at their free ends both from the upper and lower strips, and the general arrangement and spring action of all the strips in the switch 6 is the same as that described for the other switches.

These switches may be arranged in more or less circular or rectangular fashion, as indicated in Fig. 1, or in continuous alinement, as shown in Fig. 3.

The signal system which I use in connection with the above described arrangement of switches comprises a rear end signal box 22 and a forward end box 23. The rear box is divided into four compartments 24, each one of which is fronted by a word or symbol 25 denoting a signal, such words or symbols corresponding to those adjacent the various switch buttons, which are "right", "back", "left", and "stop" as previously stated. Each compartment 24 carries a lamp 26 to illuminate the corresponding signal symbol.

The forward end box 23 has also four compartments, with signal symbols and words corresponding to those on the rear box, except that the word "Pass" appears instead of "back"; the latter being only of value to be seen by a driver behind, while the word "Pass" is a signal especially for pedestrians wishing to cross ahead of the car. A lamp 27 is in each compartment of the forward signal box.

The wiring to the various compartment-lamps from the switches is as follows: A wire 28 leads from the contact 17, and is branched at its end as at 29, each branch being engageable by independent switch means 30 actuated in common by the depression of the foot brake 31 of the car. One of the switch members 30 is connected by a wire 32 to the rear end "stop" lamp, while the

other switch 30 is connected by a wire 33 to the front end "stop" lamp, it being understood that there is no electrical connection between the two switches 30.

From the members 12, 12^a, 12^b and 20, 70 wires 34 connect with the wire 33, while from the contact 20^a a wire 35 leads to the "pass" lamp of the front end box.

From the contact 13 a wire 36 leads to the "right" lamps in both signal boxes; from the contact 13^a a wire 37 leads to the "back" lamp in the rear signal box only, while from the contact 13^b a wire 38 leads to the "left" lamps in both boxes. The members 19 and 19^a are connected by separate wires 39 to the wires 36 and 38 respectively.

As is customary, the lamps and one pole of the battery are grounded on the car, the metal of which forms the return lead and enables the circuits to be completed.

The operation is as follows: Normally, that is when the switch buttons are in their inactive positions, a current may pass from the wire 9 through all the strips 8, 8^a, etc., to the wire 28. If then, without depressing any button, the brake pedal is depressed and the brakes thrown on, the two "stop" signal lamps will be automatically lit, these being the only ones affected by the closing of the switches 30.

Regardless of the closure of this circuit however, if the button 7, of the switch 3 is depressed, the circuit is first broken to the wire 28, and when the strip 8 contacts with the intermediate strip 14, which closes a circuit through strips 8, 14, and 11, member 12, and wires 34 and 32, again giving the "stop" signal, but only in the rear signal box.

Further depression of the button causes strip 11 to break from contact 12 and engage contact 13, which allows current to flow through wires 36 to give the "right" signal in both signal boxes. The result is that the driver of a car behind will first observe the warning "stop", which will be followed by "right" so that he may first get his car under perfect control, and when the last named signal appears, will be ready to act accordingly. In order to positively attract the attention of a driver behind, the operator of the signal, by suitable manipulation of the button may cause the "stop" signal to be first flashed on and off, or may cause alternate flashings of the two signals at will. The same operation is obtained with switches 4 and 5 except that these besides giving "stop" display "back" and "left" respectively.

On similarly depressing the button 15 of switch 6, the "right" and "left" signals in both boxes are given simultaneously when the strip 16 contacts with strips 21, followed by "stop" and "pass" also simultaneously, the object in giving the two opposite direction signals at the same time is to insure that the driver behind will slow up, since he

will be in doubt as to which direction the car having the signal system intends turning, if at all.

From the foregoing description it will be readily seen that I have produced such a device as substantially fulfills the objects of the invention as set forth herein.

While this specification sets forth in detail the present and preferred construction 10 of the device, still in practice such deviations from such detail may be resorted to as do not form a departure from the spirit of the invention, as defined by the appended claims.

Having thus described my invention, what I claim as new and useful and desire to secure by Letters Patent, is:—

1. An electric switch comprising, a strip free at one end, said strip being connected 20 in a circuit, another strip under the first named strip, a contact member arranged in a circuit and normally engaged by the last named strip, another contact member adapted to be engaged by the last named strip but 25 normally spaced therefrom, an intermediate strip fixed at one end to the lower strip and normally spaced from the upper and lower strips at its free end, and a button acting on the upper strip and adapted to be depressed 30 to cause the upper strip to first engage the intermediate strip, and to then cause the latter to engage the lower strip to disengage the same from the first named contact and engage it with the second named contact.

2. An electric switch system comprising a 35 plurality of spring strips fixed at one end and free at the other, said strips being disposed in continuous alinement and with their free ends contacting with the fixed

ends of adjacent strips, provision being made 40 for connecting leads to the ends of the line of strips, a button for each strip to depress the free end thereof away from the adjacent strip, a second strip under each first strip and having also a free end, a pair of 45 contacts for each second named strip, the latter being normally engaged with one of the contacts, and an intermediate spring member between each pair of first and second named strips, and normally spaced from 50 the former; said intermediate strip being engaged by the first strip with the initial depression thereof by the button and with a further depression engaging the second strip and causing the latter to be disengaged 55 from the one contact and engaged with the other; all said contacts being adapted for connection to lead wires.

3. An electric switch system comprising a 60 plurality of strips fixed at one end and free at the other, said strips being disposed in continuous alinement and with their free ends normally contacting with the fixed ends of adjacent strips, provision being made for connecting leads to the ends of the 65 line of strips, a button for each strip to depress the free end thereof away from the adjacent strip, and additional contact structures under said strips and normally independent of each other, and adapted to be 70 actuated by a corresponding strip as the latter is depressed by its button to close a circuit through the line of strips to the one depressed and thence to the corresponding 75 contact structure.

In testimony whereof I affix my signature.

RICHARD A. FINIS.
